(57) **CLAIM**

The ornamental design for an electric candle, as shown and described.

DESCRIPTION

FIG. 1 is a perspective view, taken from the front and top, of an electric candle, in accordance with our new design;

FIG. 2 is a top plan view of the electric candle of FIG. 1;

FIG. 3 is a side elevational view of the electric candle of FIG. 1;

FIG. 4 is a bottom plan view of the electric candle of FIG. 1; and,

FIG. 5 is a cross-sectional view taken along line 5—5 of FIG 1, showing, in side elevation, an electric bulb used in the electric candle of FIG. 1.
